The ornamental design for a display screen with graphical user interface, as shown and described.

6,611,206 B2 8/2003 Eshelman et al.
6,968,294 B2 11/2005 Gutta et al.**DESCRIPTION**

FIGURE is a front view of an ornamental design for a display screen with graphical user interface.

The broken lines shown in the FIGURE, that show the remainder of the graphical user interface and the display screen form no part of the claimed design.
